CLAIM

The ornamental design for a projector lens unit for a projector, as shown and described.

DESCRIPTION

FIG. 1 is a perspective view of the projector lens unit for a projector, showing the new design;

FIG. 2 is a front view thereof.

FIG. 3 is a rear view thereof.

FIG. 4 is a top view thereof.

FIG. 5 is a bottom view thereof.

FIG. 6 is a left side view thereof; and,

FIG. 7 is a right side view thereof.

The broken lines showing portions of a projector or lens unit shown in an environment of use and form no part of the claimed design.

The article according to the design of the present application is a projector lens unit for a projector which is connected and used with a projector portion of a projector.

The lens portions outlined by solid line in FIGS. 1-2, for example, are transparent. These portions are also transparent across the other views (e.g. FIGS. 4, 6, and 7).
